UNITED STATES PATENT OFFICE.

WILHELM STAVENHAGEN, OF WEEHAWKEN, NEW JERSEY.

DESIGN FOR A HAND-BAG FRAME.

No. 37,830.

Specification for Design.

Patented Feb. 20, 1906.

Application filed November 24, 1905. Serial No. 288,982. Term of patent 3½ years.

To all whom it may concern:

Be it known that I, WILHELM STAVENHAGEN, a citizen of the United States, residing in Weehawken, county of Hudson, and State of New Jersey, have invented a new, original, and ornamental Design for a Hand - Bag Frame, of which the following is a specification, reference being had to the accompanying drawing, illustrating the same and forming part thereof.

The drawing represents a plan view of a frame embodying my new design.

I claim—

The ornamental design for a hand - bag frame as shown.

WILHELM STAVENHAGEN.
